UNITED STATES PATENT OFFICE.

LEONARD A. YOUNG, OF DETROIT, MICHIGAN.

GOLF BALL.

Application filed October 20, 1927. Serial No. 227,515.

The main object of this invention is to provide a golf ball having a recessed surface which does not form or result in suction cups when the ball is struck.

Objects pertaining to details and economies of my invention will appear from the description to follow. The invention is defined and pointed out in the claims.

A structure which is a preferred embodiment of my invention is illustrated in the accompanying drawing, in which:

Fig. 1 is a plan view of a golf ball embodying the features of my invention, only a portion of the recesses in the surface being shown.

Fig. 2 is an enlarged fragmentary plan view of one of the recesses.

Fig. 3 is a detail section on line 3-3 of Fig. 2.

In the drawing similar reference characters refer to similar parts throughout the several views.

Referring to the drawing, the spherical surface 1 of the ball 2 illustrated is provided with a multiplicity of recesses 3 having concaved bottoms, these recesses being arranged closely but having substantial portions of the spherical surface of the ball between them, as is illustrated in Figs. 1 and 3.

Each recess has a star-shaped web 4, the web being formed integrally with the surface material of the ball, the edges 5 of the web being in or lying in the spherical surface of the ball, the result being that the star-shaped webs form radial partitions dividing each recess into a plurality of compartments so that when the ball is struck with a flat or smooth-faced club, the recesses do not form or produce suction cups as is likely to occur with certain golf balls having recesses of cup-like form.

My improved golf balls are accurate and have long "carrying" capacity, and may be produced without material addition to cost over balls having the meshed and dimpled surfaces now quite largely used.

Having thus described my invention, what I claim as new and desire to secure by Letters Patent, is:

1. A golf ball, the spherical surface of

which is provided with recesses having concaved bottoms and star-shaped partition webs integral with the surface material of the ball, the outer edges of the webs lying in the spherical surface of the ball, the said recesses being arranged closely but having substantial portions of the spherical surface of the ball between them.

2. A golf ball, the spherical surface of which is provided with recesses having star-shaped partition walls integral with the surface material of the ball, the outer edges of the partition walls lying in the spherical surface of the ball, the said recesses being arranged closely but having substantial portions of the spherical surface of the ball between them.

3. A golf ball, the spherical surface of which is provided with concaved recesses with star-shaped partitions integral with the bottoms thereof, the edges of the partitions lying in the spherical surface of the ball.

4. A golf ball, the spherical surface of which is provided with recesses having concaved bottoms and radially disposed partition walls, the edges of the walls being in the spherical surface of the ball.

5. A golf ball, the spherical surface of which is provided with recesses having radially disposed walls, the edges of the walls being in the spherical surface of the ball.

6. A golf ball, the spherical surface of which is provided with recesses having concaved bottom and star-shaped webs integral with the surface material of the ball, the said recesses being arranged closely but having substantial portions of the spherical surface of the ball between them.

7. A golf ball, the spherical surface of which is provided with concaved recesses with star-shaped partitions integral with the bottoms thereof.

8. A golf ball, the spherical surface of which is provided with recesses having concaved bottoms and radially disposed walls.

In witness whereof I have hereunto set my hand.

LEONARD A. YOUNG.
